DESIGN FOR A VENETIAN BLIND PIN HANGER

John M. Davis, Los Angeles, Calif.

Application April 18, 1939, Serial No. 84,365

Term of patent 3½ years

To all whom it may concern:

Be it known that I, John M. Davis, a citizen of the United States, residing at 2313 East 51st Street, city of Los Angeles, county of Los Angeles, and State of California, have invented a new, original, and ornamental Design for a Venetian Blind Pin Hanger, of which the following is a specification, reference being had to the accompanying drawing, forming part thereof.

Figure 1 is a side elevation of a Venetian blind pin hanger taken in the direction of the arrow 1 of Fig. 2 with the pin holding dog in the latching position.

Fig. 3 is an elevation similar to Fig. 1 with the pin holding dog in its open position.

I claim:

The ornamental design for a Venetian blind pin hanger, as shown and described.

JOHN M. DAVIS.
